IMPULSE DIRECTION FINDER

Günther Ulbricht, Blankenfelde, Germany, assignor to Telefunken Gesellschaft für Drahtlose Telegraphie m. b. H., Berlin, Germany

Application June 25, 1938, Serial No. 215,759
In Germany July 8, 1937

5 Claims. (Cl. 250—11)

This invention relates to impulse direction finders, particularly of the type in which the discrete impulses are viewed on a Braun tube indicator provided with a time base scanning potential. Among the objects of this invention are the provision of means for increasing the accuracy of indication by generating a scanning potential which has such a shape that the time intervals at which impulses are actually received are especially emphasized, and the application of the scanning potential to control an electronic switch by means of which the loop polarity is successively reversed to obtain automatic synchronization.

This invention will be better understood from the following description when considered in connection with the accompanying drawings, in which Figure 1 represents a saw-tooth scanning potential used in the prior art; Figure 2 represents a scanning potential in accordance with this invention; Figure 3 is a schematic diagram of an impulse direction finder; and Figure 4 is a curve representing the voltages which are applied to one of the switching tubes of the device shown in Fig. 3.

To produce a standing picture of a recurring impulse on the screen of the cathode ray oscilloscope there must be provided an alternating scanning voltage which deflects the cathode ray beam at a rate proportional to time. The alternating voltage, plotted as a function of time, customarily has the form of a saw tooth as shown in Fig. 1. Since, in general, only the center of the screen is utilized for observation of the signals, it is herein proposed to provide a deflection voltage which deflects the beam during only a portion of each cycle, as illustrated in Fig. 2. Thus the cathode ray beam moves rapidly across the screen during a portion of the time and is stationary during the remainder of the time, so that the effective time scale is decreased and the signals are drawn forth from one another.

A direction finder is known which is characterized by the following features: The voltages from a frame and from a non-directional antenna are combined so that in one position of a commutator switch the frame voltage is added to, and, in the other position the frame voltage is subtracted from the antenna voltage. The commutation may be accomplished, for example, by impressing the frame voltage upon the grids of two commutator tubes. The anodes of these tubes work in push pull, and the tubes are then alternately blocked and opened. Blocking and opening may be done by a motor switch, or the like.

According to the present invention, the deflec-

tion voltage for the cathode ray of the Braun tube is also used for the blocking and opening of the commutator tubes. This voltage preferably has the form of the curve in Fig. 2.

A voltage of this type may be obtained by applying the saw-tooth voltage illustrated in Fig. 1 to a limiting amplifier A which cuts off the negative and the positive voltage peaks. Such an amplifier is illustrated in Fig. VIII of United States Patent No. 2,086,918, wherein the amplifier is similarly used to limit the positive and negative peaks of a sine wave voltage, as shown in Figure IX of the patent.

A wiring diagram is shown in Fig. 3. The voltage from a frame antenna G is impressed in like phase on the grids of a pair of commutator tubes T, T₁ through coupling capacitors D. Out-of-phase control or keying voltages are impressed on the grids of the tubes by a center-tapped transformer U₁, the primary of which is energized by a synchronized keying and scanning relaxation oscillator K. A push-pull output transformer U₂ couples the commutator tubes to the input of an amplifier-detector HF. The voltage from a non-directional antenna H is also coupled to the input of the amplifier-detector HF. The rectified output is applied to the vertical deflecting plates of a cathode ray tube KR. The horizontal time-base deflecting voltage is obtained from the relaxation oscillator K.

It may be assumed that the impulse-frequency is 50 Hertz, then on the secondary of U₁ a voltage is induced which has the same shape as that of the primary voltage if the transformer passes frequencies up to 10,000 Hertz.

The working point of the tubes is determined by a biasing potential E_g (A in Fig. 4) whose value is such that when the received voltage is superposed on the positive wave front of the keying voltage U the tube is opened up to optimum working point (B) and on superposition of the negative wave front the tube is completely blocked as shown at (C).

Fig. 4 represents the plate current-grid voltage characteristic $J_a=f(E_g)$ of one of the commutator tubes, and shows the impulse-voltage U and the high frequency received impulses HF at the moment one of the tubes has been opened by the impulse voltage.

In Fig. 4 there is drawn only the characteristic of one tube. The working point B results from the positive wave front of the voltage U. The other tube is opened by the negative wave front of the voltage U.

Opening and blocking of the tubes may be ac-

complished also by impressing the bias voltage upon another electrode, for instance the screen grids of the tubes.

The transformer may be so designed that it transforms essentially only the sinusoidal fundamental of the impulse-voltage, for the duration of one received impulse is generally small in comparison to the period of the impulse voltage.

In either case it is necessary to control the phase relation between the received impulse and the keying impulse voltage; i. e., the impulses must arrive when first one and then the other of the keying tubes is conducting, as shown in Fig.

4. This may be accomplished in the manner described in the copending application of Sonnenstag, et al., Serial No. 194,554, filed March 8, 1938, and entitled "Impulse direction finding."

Direction finding by this device is accomplished in the customary manner. The combination of the frame antenna voltage with the nondirectional antenna voltages while alternatively reversing the phase of one of said voltages, produces the well known crossed cardioid directivity pattern. Two impulses are successively received whose respective amplitudes vary as a function of the orientation of the frame antenna. The bearing is determined by that position of the frame antenna in which the two impulses are of the same amplitude. In the case illustrated, the cathode ray is limited to alternate substantially equal periods of rest and periods of scanning. The beam moves horizontally in a given direction once for each received impulse, the return voltage being too rapid to make a perceptible trace. Consequently, the two impulses may be superimposed on the cathode ray screen, and the condition of equal impulse amplitude will be indicated by the minimum amplitude of the observed impulse, since rotating the loop in either direction causes one or the other of the impulses to become greater in amplitude.

One advantage of the arrangement according to the present invention consists in the use of an existing alternating voltage for commutation of the frame voltage, thus providing automatic synchronizing. Another advantage lies in the use of a deflection voltage having the form, illustrated in Fig. 2, such that the received impulses are drawn forth from another; thereby the reading of the impulse is more precise. The deflection voltage for the cathode ray of the Braun tube is impressed upon a time delay arrangement PH. By this means the deflection voltage is retarded so that each deflection of the cathode ray of the

Braun tube occurs during the moment at which a high frequency signal is applied to the tube.

I claim:

1. An impulse direction finder having a cathode ray oscilloscope, means responsive to periodically radiated impulses of short duration for deflecting said ray in a first direction, and scanning means for deflecting said ray in a second direction in synchronism with the period of said impulses, said scanning means including means for limiting the motion of said ray to periods of time less than the period between said impulses. 5

2. An impulse direction finder having a cathode ray oscilloscope; directive means responsive to periodically radiated impulses of short duration for deflecting said ray in a first direction; and other means for deflecting said ray in a second direction in synchronism with said impulses, said other deflecting means including means for 10 limiting the deflection of said ray in said second direction to periods of time less than the period between successive impulses. 15

3. An impulse direction finder having a cathode ray oscilloscope; a receiver having a directional antenna responsive to periodically radiated impulses of short duration, the output of said receiver being coupled to said oscilloscope for deflecting said ray in a first direction in response to said impulses; and means for deflecting said ray in a second direction, said deflecting means including an oscillator synchronized with the frequency of said impulses, and a limiting amplifier for cutting off the positive and negative peaks of said oscillations whereby said deflection 20 in said second direction is limited to periods of time less than the period between successive impulses. 25

4. A device of the character described in claim 3 which includes means for adjusting the periods of deflection of said ray in said second direction to include the times at which said ray is deflected in said first direction in response to said impulses. 40

5. An impulse direction finder having a cathode ray oscilloscope, means responsive to periodically radiated impulses of short duration for deflecting said ray in a first direction, and scanning means for deflecting said ray in a second direction in synchronism with the period of said impulses, said scanning means including means for limiting the motion of said ray to alternate substantially equal periods of rest and periods of scanning. 45
